UNITED STATES PATENT OFFICE

160,129

STOOL

Wilmot H. Scott, Clayton, Mo., assignor to Vitro Products Company, St. Louis, Mo., a corporation of Missouri

Application February 28, 1949, Serial No. 1,135

Term of patent 7 years

(Cl. D15—8)

To all whom it may concern:

Be it known that I, Wilmot H. Scott, a citizen of the United States, residing in Clayton, State of Missouri, have invented a new, original, and ornamental Design for Stools, of which the following is a specification, reference being had to the accompanying drawing, forming a part hereof.

Figure 1 is a perspective view of a stool showing my new design; Figure 2 is a side elevation thereof; and Figure 3 is a side elevation at a right angle to Figure 2, Figures 2 and 3 being on a reduced scale.

I claim:

The ornamental design for a stool, as shown.
WILMOT H. SCOTT.
